UNITED STATES PATENT OFFICE.

WILBUR S. LEWIS, OF CLEVELAND, OHIO.

HEATER FOR HAIR WAVING.

Application filed September 2, 1925. Serial No. 53,975.

This invention relates to heaters, and more particularly to heaters used in permanent waving processes.

In permanent hair waving, it is customary to provide a plurality of hollow cylindrical heater casings having spaced walls for containing electric wiring arranged to produce heat when the current is turned on. The wiring extends through apertures in the casing walls and is connected with a source of electric supply through an arbor positioned above the hair to be waved. The heaters are suspended by means of the wiring, and as they are free to swing, the wiring insulation is frayed by frictional engagement with the portions of the casings through which they pass, eventually causing short circuits and necessitating replacement of the wiring.

An object of my invention is to provide means for securing the wiring adjacent the heaters in a stationary relation therewith so that there will be no relative movement to cause the above set forth conditions.

Another object of the invention resides in providing a suspended heater with which a member is adjustably associated to secure the wiring adjacent thereto in a stationary relation.

These and other objects and the invention itself will appear in the following detailed description of one embodiment of the invention.

In the accompanying drawings, Figure 1 is a side elevation of a heater and a wiring retaining member associated therewith to secure the wiring adjacent the heater stationary relatively therewith; Fig. 2 is a transverse enlarged sectional view of the same taken on line 2—2 of Fig. 1; and Fig. 3 is another transverse sectional view taken on line 3—3 of Fig. 1.

Referring now to the drawings by characters of reference, the heater casing includes an inner cylindrical shell member 10, and an outer shell member 11. The major portion of the shells are preferably cylindrical and spaced in parallel relation. Wiring 12 is wound around the inner shell, between the shells, and arranged to produce heat when the electric current is turned on, such construction being of a conventional character which is well known in the art. An end 13 of the outer shell is spun to a diameter to engage the inner shell and is preferably secured therewith by expanding the adjacent

end 14 of the inner shell, or in any other suitable manner.

The outer shell is of considerably shorter length than the inner shell, and the space 60 between the end 15 of the outer shell and the inner shell is enclosed by a cap member 16. The inner shell extends through a central aperture in the cap member 16, and the outer edge of the cap member is pressed over the 65 end of the outer shell. The cap member is preferably secured in position by rolling a bead 17 in the inner shell, adjacent the cap member.

The wiring 12 extends through apertures 70 18 in the cap member and are suspended from an overhead support (not shown), in contact with a suitable source of electric supply.

A cylindrical sleeve member 20 is slidable 75 on the projecting end 19 of the inner shell member to secure the portion of the wiring, adjacent the cap member, in stationary relation with the heater so that the insulation covering will not be frayed by movement 80 against the aperture walls. The projecting end 19 of the inner shell is closed at its end by a wall 21, while the other end of the inner shell is open, so that it can be moved over a strand of hair, prepared for steaming, 85 to form a permanent wave therein.

The sleeve member 20 consists of a cylindrical body open at one end, and closed at the other end by a wall 22. The end wall 22 is provided with a central aperture 23 90 through which the wiring 12 extends. The inner diameter of the sleeve member is larger than the external diameter of the inner casing shell extension, and is such that it can be forced to slide over the projecting end 20 of the inner shell and tightly engage the wiring 12, thus securing it stationary with the heater at the points where it passes through the cap member of the casing. The slideable sleeve member 20 is removable from the inner shell to permit the wiring to be assembled, and longitudinally extending detents 24 are formed in the wall of the projecting end 19 of the inner casing, to align with the apertures 18 in the cap 95 member of the casing for receiving and positioning the wiring.

A strip of cork 25, or other suitable similar filler material, is placed over the end of the inner shell and extended on opposite 110 sides thereof. The sleeve member engaging with the filler member prevents binding,

so that the sleeve can be moved upon, or removed from, the inner shell. Air holes 26 are provided in the sleeve member to prevent condensation, which would be caused by enclosing the end of the inner shell when the current is turned on.

Various changes can be made in the details and arrangement of the structure herein described without departing from the 10 spirit of the invention and the scope of what I claim.

What I claim is:—

1. In a heater for permanent waving apparatus, the combination of a hollow cylindrical casing comprising an outer relatively short tube and an inner relatively long tube, the outer tube telescoped over an end of the inner tube and joined therewith at its ends, the lateral walls of the tubes being relatively spaced, an electric heater element between said walls, a tubular handle element supported in telescoped relation upon the end of the inner tube, with their lateral walls relatively spaced; and electrical circuit conductors disposed within the space between the handle inner wall and the said projecting end of the inner tube.

2. In a heater for permanent waving apparatus, the combination of a hollow cylindrical casing comprising an outer relatively short tube and an inner relatively long tube, the outer tube telescoped over an end of the inner tube and joined therewith at its ends, the lateral walls of the tubes being relatively spaced, an electric heater element between said walls, a tubular handle element supported in telescoped relation upon the end of the inner tube, ribs carried by the handle element for retaining the 30 walls of the handle in spaced relation with the walls of the inner tube, and electrical

circuit conductors disposed within the space between the handle inner wall and the said projecting end of the inner tube.

3. In a heater for permanent waving apparatus, the combination of a hollow cylindrical casing comprising an outer relatively short tube and an inner relatively long tube, the outer tube telescoped over an end of the inner tube and joined therewith at its ends, the lateral walls of the tubes being relatively spaced, an electric heater element between said walls, a tubular handle element supported in telescoped relation upon the end of the inner tube with their lateral walls relatively spaced, longitudinally extending 55 detents formed in the walls of the tubular handle, and electrical circuit conductors disposed within the longitudinal detents and the space between the handle inner wall and the said projecting end of the inner tube.

4. In a heater for permanent waving apparatus, the combination of a hollow cylindrical casing comprising an outer relatively short tube and an inner relatively long tube, the outer tube telescoped over an end of the inner tube and joined therewith at its ends, the lateral walls of the tubes being relatively spaced, an electric heater element between said walls, a tubular handle element supported in telescoped relation upon the 60 end of the inner tube with their lateral walls relatively spaced, said handle portions having apertures adjacent the upper end thereof for the escape of heat, and electrical circuit conductors disposed within the space between the handle inner wall and the said projecting end of the inner tube.

In testimony whereof, I hereunto affix my signature.

WILBUR S. LEWIS.
